CURRENT LEAD-IN SEAL FOR ELECTRIC
VACUUM TUBES AND THE LIKE

William Thomas Gibson, London, England, assignor, by mesne assignments, to International Standard Electric Corporation, New York, N. Y., a corporation of Delaware

Application March 26, 1945, Serial No. 584,801
In Great Britain March 3, 1944

10 Claims. (Cl. 49—92.5)

1

The present invention relates to thermionic valves and other like electric vacuum or gas-filled tubes, and is particularly concerned with improving the arrangements for bringing the filament lead conductors outside the envelope in high power valves.

In valves of this kind it has previously been the practice to provide two co-axial copper tubes one inside the other to convey the heating current to and from the filament. The outer tube is sealed through the envelope, and the inner tube is sealed to the outer tube by means of a re-entrant annular glass bulb at some point outside the envelope. An arrangement of this kind may be seen, for example, in British Patent Specification No. 469,584. As there is usually some considerable length of copper tube between the external seal and the filament supports, trouble is likely to be experienced when the valve heats up from differences in expansion between the two tubes. The principal object of the present invention is to eliminate the effect of the difference of expansion and to accomplish this without the use of a flexible section in one of the tubes, and by means of a simple assembly.

The invention accordingly provides an electric vacuum or gas-filled valve comprising an envelope and two coaxial metal tubes arranged one inside the other, the outer tube being sealed through the said envelope, and the two tubes being fixed together at their ends inside the said envelope by an insulating seal hermetically closing the annular space between the two tubes, and the inner tube being closed at its inside end.

The invention will be described with reference to the accompanying drawings in which Figures 1, 2, and 3 each shows a sectional view of the part of the envelope of a thermionic valve through which the lead-out conductors are sealed, each of said figures illustrating a different embodiment of the invention.

It will be convenient to describe Figs. 1 and 2 together, and the particulars given apply to both except where one of them is specially referred to. Many of the elements in these two figures are similar and are given the same designations.

As shown in Fig. 1 or 2, a valve according to the invention comprises an envelope 1 (see Fig. 1) or a reentrant envelope 1a (see Fig. 2) of glass or the like, of which only the lower part is shown. This envelope encloses the usual valve electrodes, none of which is shown. The valve is of the filamentary type cathode (not shown) which may be arranged in one or more loops as shown in the above-mentioned patent specification, for

example. The lead-out conductors for the filament comprise two co-axial metal tubes 2 and 3, preferably of copper, arranged one inside the other. The outer tube 2 is sealed through the envelope by means of a flared metal cone 4 brazed or otherwise secured thereto at 5, and sealed to the envelope 1 or 1a at the lower end 6 or 6a by a Housekeeper seal, for example. In Fig. 1, the cone 4 is turned upwards, but in Fig. 2 it is turned downwards in order to accommodate the re-entrant envelope 1a.

The outer tube 2 is flared out at its upper end, and the inner tube 3 is provided with a metal cone 7 brazed thereto. The two tubes are sealed 15 together inside the envelope 1 by means of a glass ring 8 in Fig. 1 or as shown in Fig. 2, by a small re-entrant annular channel-shaped glass bulb portion 9 sealed by Housekeeper seals to the two tubes. The inner tube 3 is hermetically 20 closed at its upper end by a solid metal plug 10 secured thereto. This plug carries at its upper end a platform 11 to which one end of the filament (or of each of the loops thereof) may be secured in any convenient way. A metal cylinder 12, as shown in Fig. 1, is secured at 14 inside 25 the envelope to the upper end of the tube 2 to which cylinder the other end of the filament or the other ends of its loops may be secured. By the alternative arrangement shown in Fig. 2, a 30 metal rod such as 13 is secured at 15 to the tube 2 to serve for the filament connection. The cylinder 12 or the rod 13 may be of any suitable length.

It is to be noted that since the two metal tubes 35 are joined together at their upper ends, there will be no appreciable relative movements of the platform 11 and cylinder 12 (or rod 13) caused by differences in expansion of the tubes when the valve becomes hot. Such movements may 40 occur at the lower ends of the tubes where they do not matter, or can easily be dealt with. Another point is that the space between the two tubes is now in effect outside the envelope instead 45 of inside as in the previous arrangement already referred to, and besides greatly simplifying the construction this also enables the tubes to be very easily cooled by means of water or air. For this purpose a hole 16 (or a series of holes) is 50 provided through the wall of the inner tube 3 at the upper end. Air or water or other cooling fluid may thus be supplied through the inner tube and exhausted from the space between the tubes.

55 The tubes 2 and 3 can clearly be made of any

suitable length outside the envelope; for example, they can be cut quite short.

Fig. 3 shows another embodiment of the invention, which though in principle the same as those shown in Figs. 1 and 2 differs therefrom in one or two particulars of practical importance. Those elements in Fig. 3 which are substantially similar to corresponding elements in Figs. 1 and 2 are given the same designations.

The two co-axial copper tubes 2 and 3 which serve as the filament leads are arranged as in Fig. 2 for a re-entrant envelope 1 which is sealed to a cone 4 brazed at 5 to the outer tube 2. The upper end of the inner tube 3 is closed by a copper disc 17 brazed thereon, and a down turned copper cone 18 is brazed on to the outside of the tube 3. The upper end of the outer tube terminates in a cone 19.

The two cones 18 and 19 are sealed by a House-keeper seal to opposite ends of a barrel-shaped ring of glass 20 which corresponds to the details 8 and 9 shown in Figs. 1 and 2 respectively. This arrangement enables the seals to be rather more easily made than the arrangement of Fig. 1 or 2, and the cone 18, which corresponds to the cone 7 of Figs. 1 and 2 is turned downwards instead of upwards for this purpose.

A copper ring 21 is brazed on to the outside of the outer tube 2 and carries one or more leads or anchors 22 for the filament (not shown). Anchors 23 for the other ends of the filament are mounted in any convenient way in the disc 17.

The two tubes 2 and 3 are spaced apart at the lower end by an annular insulator 24 which also provides some mechanical support. Two clamps (not shown) may be secured respectively to the two tubes 2 and 3 for making the connections to the external leads for the filament heating current.

The inner tube 3 has a large number of perforations 16. Air or other cooling fluid may be introduced into the tube 3 at 27 and escapes through the holes 16 for the purpose of cooling the glass ring 20 and seals to the cones 18 and 19, and may be exhausted from the space between the tubes through holes provided in the insulator 24.

The glass ring 20 may be very short since the voltage between the metal parts at its ends is only the filament voltage, which is quite low.

The filament supports 21 and 22 should be of relatively large cross-section so that they will be at substantially the same temperature as the tubes 2 and 3. Expansion or contraction of the short length between the disc 17 and the ring 21 are found to be negligible in practice, and it is easy to arrange so that the highest temperature reached in this area is from 100° C. to 150° C.

An alternative cooling arrangement is to provide a cylindrical baffle 28 in the space between the two tubes, the baffle being attached to the outer tube at the lower end of the baffle, and extending to a position between the holes 16 and the glass ring 20. A ring of exhaust holes is provided in the wall of the outer tube 2 at 29 just outside the envelope 1, and air is blown into the space between the two tubes. Part of the air is exhausted through the holes at 29, and the rest through the holes 16, and out at 27. This arrangement is a little more complicated than the simpler arrangement first described, which is, however, found to be quite satisfactory in many cases.

Although the present invention is of particular

interest in connection with high power valves which generally employ directly heated cathodes, it is evident that the tubes 2 and 3 in any of the embodiments could be used for the lead out conductors for the heater of an indirectly heated cathode.

The arrangement of the invention has the following advantages:

1. It has a rotational symmetry throughout, so that all machining and glass working can be easily done on a lathe.

2. The adverse effects of unequal expansion are avoided.

3. It provides a very simple means for leading very heavy currents into a valve.

4. It enables cooling to be easily applied to the filament lead out conductors.

5. The length can be quite short, since the tubes are joined inside the envelope.

What is claimed is:

1. A current lead-in seal for use in a hermetically sealed device having an envelope wherein the lead-in conductors undergo wide changes in temperature, said seal comprising a pair of concentric metallic tubes having one end thereof normally disposed inside of said sealed device, means for hermetically plugging the inner tube at said one end, an annular ring of insulating material sealed to said inner and outer tubes adjacent the one end thereof and sealing the space between said tubes, and an annular ring of metal sealed to said outer tube, a portion of said annular ring of metal at a region removed from said outer tube being adapted for sealing to said envelope.

2. The structure of claim 1 wherein means are provided between said tubes for supporting said tubes relative to each other at a portion remote from said one end to provide a rigid structure.

3. A current lead-in seal for use in a hermetically sealed device having an envelope wherein the lead-in conductors undergo wide changes in temperature, said seal comprising a pair of concentric metallic tubes having one end thereof normally disposed inside of said sealed device, insulating material fused to said tubes at said one end and forming a rigid sealing connection therebetween, means for hermetically plugging the inner tube at said one end, and means hermetically sealed to the outer tube at a zone near said one end and being adapted for sealing to said envelope.

4. The structure of claim 3 wherein the means for sealing to the envelope comprises a metal cone having the small end sealed to said outer tube and the flared end adapted for sealing to said envelope.

5. The structure of claim 3 wherein said inner tube has passages through the walls thereof giving fluid access to the annular region between said two concentric tubes whereby cooling fluid may be circulated.

6. A current lead-in seal for use in a hermetically sealed device having an envelope wherein the lead-in conductors undergo wide changes in temperature, said seal comprising a pair of concentric metallic tubes having one end thereof normally disposed inside of said sealed device, insulating material bridging the annular space between said tube ends at said one end and forming a rigid hermetic sealing connection therebetween, a metallic member hermetically plugging said inner tube at said one end and providing a platform from which electrodes may be supported, and an annular metal member sealed

to said outer tube along a narrow circular zone and sealed to said envelope material along a narrow circular zone.

7. The structure of claim 6 wherein said concentric tubes are flared at said one end with said metallic member being disposed in the cylindrical part of said inner tube.

8. The structure of claim 6 wherein said inner tube has apertures therethrough giving access to the annular space between said tubes whereby cooling fluid may be circulated between said two concentric tubes.

9. A current lead-in seal for use in a hermetically sealed device having a glass envelope wherein the lead-in conductors undergo wide changes in temperature, said seal comprising a pair of concentric metallic tubes having one end thereof normally disposed inside of said glass envelope, glass fused to said tubes at said one end and forming an annular seal between said tubes, a metal plug hermetically sealing the inner tube at said one end, and a metal ring surrounding said outer tube and having one portion sealed thereto and having another portion sealed to said glass envelope, said ring providing a hermetic

25 circular seal between said glass envelope and outer tube.

10. A current lead-in seal according to claim 3 wherein a metallic cone is sealed to said inner tube, said metallic cone extending towards said outer tube, said outer tube being terminated by a cone extending towards said metallic cone, and said sealing means comprises a barrel-shaped insulating portion sealed between the opposite ends of said cones.
